APPARATUS FOR ELIMINATING INTERFERENCES IN RADIO RECEPTION

Pierre Louis Victor Lambert, St. Martins, Guernsey, Channel Islands, assignor of two-fifths to Harold Hickman Randell, Guernsey, Channel Islands

Application May 23, 1933, Serial No. 672,423
In Great Britain May 26, 1932

7 Claims. (Cl. 250—20)

This invention has reference to wireless (radio) receiving apparatus and relates to circuit arrangements to be connected to or incorporated in such apparatus for the purpose of eliminating the effect of radio-frequency interferences induced in the aerial circuit of the receiver by electric conductors used in feeding the receiver, particularly the power and light mains or lines; the object being to eliminate the effects of interfering currents in the primary oscillatory circuit of the receiver by the employment of means adapted to render equal the respective potential differences to earth on the aerial and earth sides of the said circuit due to the interfering currents and independently of the frequency of the said currents.

To this end, the circuit arrangements comprise:—(a) a means to establish or vary the mutual inductance and capacitance coupling, M , between the aerial circuit and the electric lines carrying the interfering currents; (b) a means to establish or vary, for the interfering currents, the electric coupling between the cathode earth side of the primary oscillatory circuit of the receiver and the said electric lines or conductors.

In carrying the invention into effect, the varying referred to under (b) is obtained by placing in series in either or both of the leads from the distributing mains, a parallel circuit composed of an inductance of definite impedance to the interfering currents, through which inductance the current from the mains used for feeding the receiver passes and, in parallel with such inductance, a fixed or variable condenser in series with a fixed or variable resistance, whereby the amplitude and phase-angle of the interfering currents in the said parallel circuit so formed are adapted for regulation.

The varying referred to under (a) which may be dispensed with if certain conditions are met naturally, is obtained by placing a variable electric coupling between the aerial lead-in and a point (P) on the mains side of the circuit referred to in (b), such point being formed by placing (in series) across the mains lead a condenser of such capacity as will bring the mains leads at that point at an equal electrical high frequency difference of potential to earth. The coupling (a) combines with the filter (b) in such a manner as to make equal the phase-angle and amplitude of the interfering potential differences to earth on each side of the primary oscillatory circuit of the receiver for all frequencies whereof the corresponding impedance of the primary circuit is not negligible.

Under certain conditions of earthing of the mains, it will be necessary to place, on the mains side of the above mentioned point (P) on one or both mains leads, a circuit similar to that hereinbefore described as (b) to regulate the high frequency resistance between the point (P) and the earth.

In the accompanying drawing:—

Figure 1 is a diagrammatic representation of the circuit arrangement of which the function is similar to that of a Wheatstone bridge.

Figure 2 is a diagrammatic representation of the practical realization of the circuit arrangement applied to an all-mains wireless receiver, there being a variable impedance on the lead consisting of a variable inductance and condenser in parallel and a variable resistance and condenser in series.

Figure 3 is another diagrammatic representation of the practical realization of the circuit arrangement having similar characteristics to that of Figure 2 and showing a variable impedance consisting of a variable condenser and inductance in parallel and a lead to earth through a condenser and earth resistance.

Referring first to Figures 2 and 3:—

Let it be assumed that X , X' indicates a portion of a distributing main (with one side earthed, say X) feeding the receiver Z' . It is required that the unwanted electric waves or transients carried along X , X' should not interfere with the ultimate purpose of the receiver by their electrokinetic effect or by the electrostatic field they create or by the electromagnetic waves due to them which may be induced into the aerial system of the receiver Z' through the mutual inductance and capacity coupling mainly due to the inductances and capacities K^2 , K^3 , K^4 existing naturally between the aerial, the mains X , X' and the earth (a natural direct coupling between X , X' and aerial is not represented in the drawing) or through any coupling that may be made for instance, through the variable condenser K' , designating the resultant coupling M .

Z generally placed on the positive lead, is a variable impedance and may consist of:—

(i) an inductance, fixed or variable, with or without variable condenser in parallel, or

(ii) any band-pass device used in the tuning of wireless receivers, and

(iii) a variable resistance R and condenser in series arranged in parallel with (i) or with (ii).

D generally placed in the negative lead is a variable impedance consisting of:—

- (a) an inductance, or
- (b) a low frequency choke, the inductance of which will depend upon the amount and frequency of hum to be eliminated, or
- (c) a combination of (a) and (b), and
- (d) a variable resistance R' and condenser in series arranged in parallel with (a) or/and (b).

10 The current feeding the receiver will pass through (i) or (ii) of Z and through (a) (b) or (c) of D.

L, L' are leading impedances preceding the bridge either or both of which may be used and 15 which may be composed of pure inductances or circuits such as referred to in connection with Z.

The resistance R, r' could be replaced by another connection to earth. Figure 3 shows an earth connection T' in the place of the resistance 20 R (Figure 2), the connection being made with X at B through the condenser C⁴. Thus it will be seen that the resistance R is replaced by the resistance of the natural path between the two earth connections T, T' plus the resistance of contact and it would be possible by suitably varying either or both of such connections to obtain a required value of resistance.

At T, R⁴ represents the value of the impedance between the device and the earth; this earth connection is the only one required for the receiver 30 and the device and can be made on either branch in a or a'.

R³ represents the value of the impedance between the electric lines and the earth; this impedance may be increased by L or decreased by 35 making a better earth connection at a suitable point of the line to regulate the voltage V across the bridge created by the interfering currents (Figure 1).

40 C' represents a condenser placed across the mains leads at points taken on the mains side of Z and D to bring such points of the leads at an equal high frequency difference of potential to earth (thus determining the electric point P) (Figure 1).

C² represents a condenser placed across the mains leads on the receiver side of Z and D.

C³ represents a condenser in series between the earth connection and a point taken between 50 Z or D and the oscillatory circuit of the receiver.

The condenser indicated at K², K³, K⁴ in Figure 1 is not representative of the capacity value existing between aerial and earth; this value is represented by K² in Figures 2 and 3, but it implies 55 that K², K³, K⁴ combine, together with a certain inductance and capacitance existing between aerial and mains (not represented in the drawing), to form the induced voltage V' (Figures 2 and 3) between aerial and earth.

60 The voltage V across the bridge is considered as if the inductances L, L' were short circuited.

There is no resistance introduced in the oscillatory circuit of the set, a direct connection to earth being obtained in the arrangement shown 65 in Figures 2 and 3 through b', a', C², a, C³, R⁴; any resistance to this oscillatory circuit which might be placed in the set should be shunted by a condenser of sufficient capacity. Such a case would occur if the device were placed on the mains side of the transformer when the mains are carrying alternating current in which case the question of polarity, referred to in the next 70 succeeding two paragraphs and elsewhere in this specification, does not arise as it does in the case

of the mains carrying direct current or if the device is placed after the rectifier.

A circuit such as Z or D may replace the impedance found on the positive side of an all-mains wireless receiver between a and the cathode-heating circuit (Figs. 2 and 3). 80

On the negative side there must be no impedance between a' and the aerial oscillatory circuit; D will be in series with the negative lead on the mains side of a'. 85

In the case of a set getting only its anode current from the mains it will be necessary to connect the points a and a' to the filament (for instance to the cathode-heating battery) through condensers of sufficient capacity and to the anode current-supplying unit in the ordinary way. 90

Referring now to Figure 1—in reality a diagrammatic representation of Figures 2 and 3 showing that the function thereof is similar to that of a Wheatstone bridge, the interfering currents carried along the distributing main X, X' create a voltage (V) across the diagonal X—T of the bridge, while the oscillatory circuit of receiver Z' to be protected therefrom is operable across the other diagonal of the bridge (viz: that 100 wherein the galvanometer is normally placed).

The natural couplings between aerial and mains (not represented in the drawing) and between mains and earth create a voltage V' (Figures 2 and 3) between aerial and earth. 105

If V² be regarded as the resulting voltage due to V between T and the end of the diagonal shown in Figure 1 on the left of Z', and if V³ be regarded as the resulting voltage between T and the other end of the same diagonal, the 110 equilibrium of the bridge will be obtained when V' + V² = V³, and when the phase-angle of (V¹ + V²) equals the phase-angle of V³.

The equilibrium so obtained is maintained by the correct adjustment of the device for a range 115 of frequencies depending upon the frequency at which the primary oscillatory circuit of the receiver is tuned.

The correct adjustment of the variable impedances of (D, Z) and K' will give this equilibrium (D, Z) being one impedance (to the interfering currents) composed of D and Z in parallel. 120

In some cases the natural value of coupling (that is the capacity existing naturally between 125 aerial, lead-in and earth) may satisfy the desired relation between the quantities K², R⁴, K' (Z, D) thus indicating a form of the invention in which the variable condenser K' may be dispensed with.

The values of the components used in the circuits herein described may be computed from the following figures:—

The h. f. inductances of Z, L and L' may vary 130 between 0 and 4000 microhenries.

The resistance of R and R' may vary between 0 and 5000 ohms.

The capacity of the condensers in series with R and R' may vary between 0.001 and 2 microfarads. 140

The capacity of K' may vary between 0 and .0005 microfarads.

The capacity of the condensers C' and C² may vary in microfarads up to 20 microfarads and that of the condenser C³ up to infinity. 145

The complete device may be placed in or near the receiver or at a distance from it.

I claim:—

1. In wireless receiving apparatus, for eliminating the effect of radio-frequency interferences 150

- induced in the aerial circuit by electric lines used in feeding the receiver, a device which consists of circuit arrangements comprising a filter composed of two inductances through which the current feeding the receiver is passed and whereof one is placed in series in each lead of the distributing mains, there being placed on each side of said inductances in series across the mains leads a condenser to bring the mains leads at these points at an equal electric high frequency difference of potential to earth and, in parallel with the said inductances a variable condenser in series with a variable resistance, the said filter being interposed at a point between the mains leads and the receiver and the mains side of the filter being electrically coupled by means of a variable condenser and a variable resistance in series to one point of the aerial lead-in while the receiver side of the filter is earthed, all impedances between this earthing point and the earth cathode side of the primary oscillatory circuit of the receiver being shunted by condensers. 80
2. In wireless receiving apparatus for eliminating the effect of radio-frequency interferences induced in the aerial circuit by electric lines used in feeding the receiver, a device which consists of circuit arrangements comprising a filter composed of a fixed inductance of high impedance to the interfering currents in series in one of the mains leads while in the other mains lead there is a variable inductance, there being placed on each side of the said inductances and in series across the mains leads a condenser to bring the mains leads at these points at an equal electric high frequency difference of potential to earth and placed in parallel with the said inductances a variable condenser in series with a variable resistance, the said filter being interposed at a point between the mains leads and the receiver and the mains side of the filter being electrically coupled by means of a variable condenser and a variable resistance in series to one point of the aerial lead-in while the receiver side of the filter is earthed and the electric continuity is established between the earthing point of the filter and the earth-cathode side of the primary oscillatory circuit of the receiver by means of a condenser, impedances between the earthing point of the filter and the earth-cathode side of the primary oscillatory circuit being shunted by condensers. 100
3. In wireless receiving apparatus for eliminating the effect of radio-frequency interferences induced in the aerial circuit by electric lines used in feeding the receiver, a device which consists of circuit arrangements comprising a filter composed of two inductances through which the current feeding the receiver is passed and whereof one is placed in series in each lead of the distributing mains, there being, in parallel with the said inductances, a variable condenser in series with a variable resistance, and there being placed on the receiver side of the said inductances and in series across the mains leads a condenser to bring the mains leads at these points at an equal electric high frequency difference of potential to earth while on the mains side of the said inductances there is placed in series across the mains leads a condenser in series with a variable resistance, the said filter being interposed at a point between the mains leads and the receiver and the mains side of the filter being electrically coupled by means of a variable condenser and a variable resistance in series to one point of the aerial lead-in while the receiver side of the filter is earthed, all impedances between this earthing point and the earth-cathode side of the primary oscillatory circuit of the receiver being shunted by condensers. 120
4. In wireless receiving apparatus for eliminating the effect of radio-frequency interferences induced in the aerial circuit by electric lines used in feeding the receiver, a device which consists of circuit arrangements comprising a filter composed of a fixed inductance of high impedance to the interfering currents in series in one of the mains leads while in the other mains lead there is a variable inductance there being placed in parallel with the said inductances a variable condenser in series with a variable resistance, the said filter being interposed at a point between the mains leads and the receiver and the mains side of the filter being electrically coupled by means of a variable condenser and a variable resistance in series to one point of the aerial lead-in while the receiver side of the filter is earthed, all impedances between this earthing point and the earth cathode side of the primary oscillatory circuit of the receiver being shunted by condensers. 140
5. In wireless receiving apparatus for eliminating the effect of radio-frequency interferences induced in the aerial circuit by electric lines used in feeding the receiver, a device which consists of circuit arrangements comprising a filter composed of a pair of inductances through which the current feeding the receiver passes and whereof one is placed in series in each lead of the distributing mains, there being placed on each side of the said inductances in series across the mains leads a condenser to bring the mains leads at these points at an equal electric high frequency difference of potential to earth and in parallel with the said inductances a variable condenser in series with a variable resistance, the filter being interposed at a point between the mains leads and the receiver and the mains side of the filter being electrically coupled by means of a variable condenser and a variable resistance in series to one point of the aerial lead-in while the receiver side of the filter is earthed and the electric continuity is established between the earthing point of the filter and the earth-cathode side of the primary oscillatory circuit of the receiver by means of a condenser, impedances between the earthing point of the filter and the earth-cathode side of the primary oscillatory circuit being shunted by condensers. 160
6. In wireless receiving apparatus for eliminating the effect of radio-frequency interferences induced in the aerial circuit by electric lines used in feeding the receiver, a device which consists of circuit arrangements comprising a filter composed of two inductances through which the current feeding the receiver passes and whereof one is placed in series in each lead of the distributing mains there being a low frequency choke in series with the inductance on one side of the filter and on each side of the said inductances in series across the mains leads a condenser to bring the mains at these points at an equal electric high frequency difference of potential to earth and, in parallel with the said inductances, a variable condenser in series with a variable resistance, the filter being interposed at a point between the mains leads and the receiver and the mains side of the filter being electrically coupled by means of a variable condenser and a variable resistance in series to one point of the aerial lead-in while the receiver side of the filter is earthed, all impedances between this earthing point and the earth-cathode side of the primary oscillatory circuit of the receiver being shunted by condensers. 180
7. In wireless receiving apparatus for eliminating the effect of radio-frequency interferences induced in the aerial circuit by electric lines used in feeding the receiver, a device which consists of circuit arrangements comprising a filter composed of a pair of inductances through which the current feeding the receiver passes and whereof one is placed in series in each lead of the distributing mains there being a low frequency choke in series with the inductance on one side of the filter and on each side of the said inductances in series across the mains leads a condenser to bring the mains at these points at an equal electric high frequency difference of potential to earth and, in parallel with the said inductances, a variable condenser in series with a variable resistance, the filter being interposed at a point between the mains leads and the receiver and the mains side of the filter being electrically coupled by means of a variable condenser and a variable resistance in series to one point of the aerial lead-in while the receiver side of the filter is earthed, all impedances between this earthing point and the earth-cathode side of the primary oscillatory circuit of the receiver being shunted by condensers. 200

nating the effect of radio-frequency interferences induced in the aerial circuit by electric lines used in feeding the receiver when such receiver is fed through a transformer, a device which
 5 consists of circuit arrangements comprising a filter composed of two inductances through which the current feeding the receiver passes and whereof one is placed in series in each lead of the distributing mains, there being included in
 10 series with the inductance on one side of the filter a low-frequency choke and the electric coupling being established between the lead-in and the electric mains at a point in the latter preceding the transformer, also placed on each
 15 side of the said inductances in series across the mains leads a condenser to bring the mains

leads at these points at an equal electric high frequency difference of potential to earth and, in parallel with the said inductances, a variable condenser in series with a variable resistance, the said filter being interposed at a
 80 point in the mains leads between the transformer and the receiver and the mains side of the filter being electrically coupled by means of a variable condenser and a variable resistance in series to one point of the aerial lead-in while the receiver side of the filter is earthed, the
 85 impedances between this earthing point and the earth-cathode side of the primary oscillatory circuit of the receiver being shunted by condensers.
